UNITED STATES PATENT OFFICE.

RICHARD I. EGGLESTON, OF PHILADELPHIA, PENNSYLVANIA, AND
FREDERICK OLIVER, OF CHARLOTTE, NORTH CAROLINA.

MATTRESS-STUFFING MACHINE.

SPECIFICATION forming part of Letters Patent No. 630,201, dated August 1, 1899.

Application filed April 19, 1899. Serial No. 713,665. (No model.)

To all whom it may concern:

Be it known that we, RICHARD I. EGGLESTON, a resident of Philadelphia, county of Philadelphia, and State of Pennsylvania, and 5 FREDERICK OLIVER, a resident of Charlotte, county of Mecklenburg, and State of North Carolina, citizens of the United States, have invented certain new and useful Improvements in Mattress-Stuffing Machines; and we 10 do hereby declare the following to be a full, clear, and exact description of the invention, such as will enable others skilled in the art to which it appertains to make and use the same.

Our invention relates to mattress-stuffing devices, and has for its object certain improvements, hereinafter described and claimed, whereby the operation of stuffing a mattress-tick is more easily and satisfactorily performed and the filling delivered uniformly to 20 the tick.

Our invention will be understood by reference to the accompanying drawings, wherein the same parts are indicated by the same letters throughout the several views.

25 Figure 1 is a view, partly in longitudinal section and partly in plan, showing our apparatus as in the position for expelling a charge from the box into the mattress case or tick, the cover of the box, however, being open. 30 Fig. 2 is a vertical longitudinal section of the apparatus, taken on the line 2 2 in Fig. 1, the cover being closed. Fig. 3 is a cross-section taken on the line 3 3 in Fig. 2, looking to the left. Fig. 4 is a rear elevation of the follower 35 with its hinged back let down. Fig. 5 is a similar view of the same with the cable omitted. Fig. 6 is a detail perspective view of one of the slats for confining the filling in a mass. Fig. 7 is a fragmentary perspective view of 40 the forward ends of a pair of the confining slats, showing the addition of means for securing the ends together in an easily-detachable manner. Fig. 8 is a front elevation of the delivery-hood of the box; and Fig. 9 is a 45 view similar to Fig. 1, showing a modified arrangement of the cable for advancing and retracting the follower-head.

A represents the filling box or casing, which is rectangular in shape and of the size of the 50 mattress to be filled. This box has permanent

bottom and sides and is closed at its rear end A' and open at its forward or delivery end, which is fitted with a delivery-spout B, over which the tick or casing C may be placed, as seen in Fig. 1. The box is provided with a lid or top 55 A², which is hinged to the rear end of the box A', so as to be opened and closed at will. Any suitable means, such as hooks a² a², may be provided for securing the cover in its closed position.

D represents a follower, which is of a length and thickness to fit transversely within the box A and to be moved longitudinally therethrough. The said follower consists, preferably, of a solid block, which may be grooved 65 at d¹ along its rear face and at d² d² across its ends for the passage of a cable E or other means for drawing the follower through the box. This block is also provided with a series of wider grooves d³, which extend from 70 the face of the block at its upper side backward across the top, downward across the back, and forward across the bottom, as seen in Fig. 5. These grooves are provided for the reception of flexible attachments, such as flat 75 straps F' upon the rear ends of the slats F.

The slats F, of any suitable number, are of sufficient length to extend from the face of the follower-block D, when the latter is in its extreme rearward position, to or near the delivery end of the box A, as seen in Figs. 1, 2, and 9.

The flexible connections F' (shown as leather straps) are secured to the rear ends of the slats F, and extending along the portions of the 85 grooves d³, across the upper and lower sides of the follower-block D, are secured at the back of the said follower-block by engagement with studs d' d' in the said grooves at the back of the follower-block, as seen in Figs. 90 2 and 4. Instead of leather straps, as shown, however, we may employ any other suitable connection, such as metallic straps provided each with a double hinge, such as will allow the upper set of said slats F not only to be 95 turned backward out of the way when filling the box A, but which will allow their rear ends to move upwardly with respect to the follower when they have passed the forward edge of the box-cover A' at the forward point 100.

of the travel of the follower. This latter effect is important in order to release the filling from the slats when the follower is retracted.

Each slat F is stiff and has a shoulder f, 5 which abuts against the forward face of the follower-block when the rear ends of said slats are confined, as by the cover of the box being closed, so that during the forward movement of the follower these slats are projected, along 10 with the filling, into the mattress-case; but when the follower reaches the mouth of the box A the shoulders f upon the rear ends of said slats will become disengaged from the face of the block by reason of the pressure of 15 the filling material, thus releasing the slats from the filling, as above referred to. The forward ends of said slats may be left free, as seen in Figs. 1, 2, and 9, or, as shown in Fig. 7, an arrangement for connecting these 20 ends may be provided. This connection must allow of a ready disengagement when the follower and slats are to be retracted after projecting the filling into the mattress-case. Thus the upper slat F³ has a rounded stud f³ 25 on its forward end, and the lower slat F⁴ has a flexible strap F⁵ attached to its forward end, the said strap having an eye f⁵ near its free end which passes readily over the stud f³.

When a charge of filling has been forced 30 into its case and the follower is to be retracted, the upper slat F³ is disengaged from the strap F⁵ by a slight backward pull by the hand of the attendant, and the strap being thus freed will be drawn out with the under slat F⁴.

35 A backing-plate D² is hinged upon the back of the follower D and when closed covers the back thereof completely, serving to retain the flexible slat connections F' in engagement with their respective studs d'. A pivoted 40 catch d⁴ is provided for engaging the said backing-plate in its closed position and securing it.

We may employ any means for advancing and retracting the follower; but we have 45 shown in Fig. 1 a simple means consisting of a cable E, attached at its ends to drums G', provided with a turning crank G², the said cable reeving over pulleys g upon the forward part of the box A and running behind the follower-block engaging in the grooves d⁰ and d². The side members A² of the box A are longitudinally grooved for the passage of said cable, as seen at a³ in Fig. 1. In this arrangement the follower is advanced by winding the 55 cable on the drums G' through the medium of the crank G², mounted upon the shaft G³, common to the said drums, or we may use two endless cables, or equivalent means, such as sprocket-chains and gears, (indicated by 60 H in Fig. 9,) the said cables being connected to the ends of the follower-block, as at h, and reeving over pulleys h' and h² upon the forward and rear ends, respectively, of the box A. These cables are wound so as to advance 65 or retract the follower by means of a crank H', mounted upon the shaft H², carrying bevel-gears h³, meshing with other bevel-gears rig-

idly connected with the pulleys h² at the rear end of the box A. By this arrangement a simple turning of the crank H' in one direction will carry the follower forward to the extreme limit, and a simple reverse motion of the said crank will cause the follower to return to its retracted position.

We do not wish to limit ourselves to any 75 particular arrangement of means for advancing or retracting this follower, and the means herein shown are for the sake of illustration and as embodying simplicity in operation.

As seen in Fig. 1, the mattress-casing C is 80 fitted over the spout or hood B in a wrinkled or folded position, as indicated in Fig. 1, so that as the follower and the mass of filling inclosed between the slats F in front of the follower and the slats also are forced forward 85 the said casing becomes extended until it reaches its limit of extension, at which time the mass of filling will have been forced into the casing, as will be readily understood.

Having thus described our invention, what 90 we claim as new, and desire to secure by Letters Patent of the United States, is—

1. In a mattress-stuffing machine, the combination with a follower-block provided with transverse grooves; of a plurality of stiff 95 slats; and flexible connections between said slats and the rear of said follower-block arranged to lie in the said grooves, substantially as described.

2. In a mattress-stuffing machine, the combination with a follower-block, of a plurality of stiff slats having shoulders at their rear ends arranged to abut against the forward face of said follower-block; and flexible connections between the rear ends of said slats 105 and the rear of said follower-block, substantially as described.

3. In a mattress-stuffing machine, the combination with a follower-block; of a plurality of stiff slats at the upper and lower edges of 110 the said follower-block; flexible connections between the rear ends of said slats and the said follower-block; and detachable connections between the forward ends of pairs of the said slats, substantially as described.

4. In a mattress-stuffing machine, the combination with a follower-block provided with transverse grooves upon its upper and lower faces; flexible straps connected to the rear of 115 said follower-block and arranged to lie in the said grooves upon the upper and lower faces of said block; and stiff arms secured to the said flexible straps at the forward edge of said block and extending in advance thereof, substantially as described.

5. In a mattress-stuffing machine, the combination with a follower-block provided with transverse grooves upon its upper and lower faces; flexible straps connected to the rear of 120 said follower-block and arranged to lie in the said grooves upon the upper and lower faces of said block; stiff arms secured to the said flexible straps at the forward edge of said block and extending in advance thereof; and

flexible detachable connections between the forward ends of pairs of said arms, substantially as described.

6. In a mattress-stuffing machine, the combination with a rectangular box, a follower-block mounted transversely therein and movable therein; a plurality of stiff arms having flexible connection with the upper edge of said follower-block and extending in advance thereof, said arms being arranged to confine the filling material in said box; and means for continuously advancing the follower-block, substantially as described.

7. In a mattress-stuffing machine, the combination with a rectangular box, a follower-block mounted transversely therein and movable therein; a plurality of stiff arms having flexible connection with the upper edge of said follower-block and extending in advance thereof; said arms being arranged to confine the filling material in said box; means for continuously advancing the follower-block with the said arms; and means for continuously retracting the said follower-block with the said arms, substantially as described.

8. In a mattress-stuffing machine, the combination with a rectangular box and a movable follower therein; of a plurality of arms carried in advance of the said follower-block; one set of said arms being connected at their rear ends to the upper face of the said follower-block by flexible connections which will allow the rear ends of said arms to be forced

outwardly by the pressure of material within said box when exterior pressure is removed from the said arms, substantially as described. 35

9. In a mattress-stuffing machine, the combination with a follower-block; of upper and lower sets of stiff arms having flexible connections at their rear ends with the upper and lower faces respectively of said follower-block; and flexible connections between pairs of said arms at their forward ends, substantially as described.

10. In a mattress-stuffing machine, the combination with a follower-block; of upper and lower sets of stiff arms having flexible connections at their rear ends with the upper and lower faces respectively of said follower-block; flexible straps connected to the forward ends of one set of slats and provided with openings near said ends; and studs upon the forward ends of the other set of said arms, attached to engage the said openings in said straps, and thus clamp said arms upon the filling material, substantially as described. 50 55
